UNITED STATES PATENT OFFICE.

JAMES K. PUTNAM, OF TULSA, OKLAHOMA.

PUMP.

1,343,157.

Specification of Letters Patent.

Patented June 8, 1920.

Application filed April 10, 1919. Serial No. 239,047.

To all whom it may concern:

Be it known that I, JAMES K. PUTNAM, a citizen of the United States, residing at Tulsa, in the county of Tulsa and State of Oklahoma, have invented certain new and useful Improvements in Pumps; and I do declare the following to be a full, clear, and exact description of the invention, such as will enable others skilled in the art to which it appertains to make and use the same.

This invention relates to pumps, and it relates more specifically to an improved petroleum pump.

The main object of this invention is to provide a petroleum pump which is automatically lubricated with strained oil, the straining of the lubricating oil being accomplished during the pumping of the oil from the oil well.

A further object is to provide a pump of this character with a straining and filtering means which is exceedingly efficient in eliminating sand and grit from the lubricating oil, and which applies the thus filtered oil directly upon the working surface of the pump valve and other working or rubbing surfaces.

Another object of the invention is to provide an improved supporting and limiting device which supports the working valve and its adjuncts, and which also supports a sand-trap and a sand excluding washer, the latter preventing the accumulation of sand around the periphery of the supporting device, so that such accumulation of sand will not prevent the supporting device and working valve from being withdrawn from the working barrel and tubing of the pump.

Another object is to provide a simple and very efficient cushioning means which prevents the operation of the pump from wedging the supporting device in the working barrel to such an extent as to prevent the comparatively easy removal of the supporting device.

Other objects and advantages may become apparent to persons who read the following details of description in connection with the accompanying drawings, in which:—

Figure 1 is a longitudinal sectional view, the section being taken through the pump casing and working cylinder, while the remaining elements of the device are shown in elevation.

Fig. 2 is a view somewhat similar to Fig.

1, but showing all the parts except the valve stem and valve balls in longitudinal section.

Fig. 3 is an enlarged longitudinal sectional detail view.

Fig. 4 is a transverse sectional view along 60 the line 4—4 of Fig. 3.

Referring to these drawings in detail, in which similar reference characters correspond with similar parts throughout the several views, the pump casing or tubing 5 may be of any appropriate kind and includes ordinary collars or connections 6. The pump rod 7 may also be of ordinary construction and operated in the ordinary way for reciprocating the working valve through 70 the medium of its valve stem 8, the latter having a head 9 which is internally screw-threaded to receive the externally screw-threaded lower end of the rod 7. The lower end of the valve stem 8 has a screw-threaded 75 connection, as indicated at 10, with the ball cage 11 which forms a part of the working valve which is generally indicated by the numeral 12. This working valve also comprises a section of pipe 13 around which a 80 plurality of flexible washers 14 are fitted, and the upper washers have their peripheral flanges turned upward, whereas the lower ones have their peripheral flanges turned downward. This working valve is slidable 85 up and down in the working barrel 15, and a standing valve 17 is provided at the lower end of the barrel 15 for co-operation with the working valve in a manner which is well known to persons who are familiar with the 90 art.

The upper end of the working barrel has its inner surface outwardly flared as indicated at 18, and the surface 18 is preferably 95 smooth and polished, and receives the downwardly tapering or reduced lower end of the supporting member or housing 19, the flare of the working barrel and the taper of the housing being very gradual, so that the interlapped or inserted relation of the housing to the working barrel tends to hold them in perfect axial alinement with one another. Moreover, this relation insures such a tight fitting joint between the members 15 and 19 that sand and grit cannot pass therethrough. 105 The housing 19 comprises an outer tube 20, an inner tube 21 and a screw-threaded boss 22, the latter substantially comprising an extension of the inner tube 21, and this inner tube with its extension is open throughout 110

its length, so that the valve stem 8 can extend therethrough, and so that the oil passes therethrough when being pumped. A flexible washer 23 surrounds the boss 22 and has its periphery pressed against the inner surface of the casing or tubing 5 so as to exclude sand and grit from the joint between the tubing or casing and the supporting member. A lock nut 24 engages with the threads of the boss 22 and holds the washer 23 in its useful position.

A sand-trap 25, having notches in its lower edge, is seated upon the upper end of the boss 22 and nut 24, this sand-trap having a central aperture through which the valve stem 8 extends and slides, the sand-trap also being adapted to rise above the boss 22 when oil is being pumped through the inner tube 21. A spring 27 surrounds the valve stem between the head 9 and sand-trap 25, and its spring co-operates with the head 9 to stop the downward movement of the working valve before it reaches the standing valve, its spring action also cushioning the shock which would otherwise be sustained by the working valve and its adjuncts at the end of their downward stroke. Moreover, the spring 27 serves as a cushion for the sand-trap 25 in its upward movement.

The inner tube 21 and outer tube 22 are united at their upper ends, and the internal diameter of the outer tube is considerably greater than the outer diameter of the inner tube, so that an annular space 28 is provided between the tubular elements 20 and 21. A working tube 29 has its lower end somewhat enlarged, as shown at 30, so as to have sliding engagement with the working barrel 15, and this portion 30 is internally screw-threaded and thereby engaged with the ball cage 11. At a short distance above the enlarged portion 30, the working tube 29 is formed with an annular shoulder 31, and an annular shoulder 32 is formed therein at a considerable distance above the shoulder 31. Between the shoulders 31 and 32, the working tube is provided with a plurality of annular series of perforations 33. The upper end portion of the working tube 29 is slidably fitted within the housing or duplex tubular member 19, and the length of the working tube 29 is such that a portion thereof is always within the outer tube 20.

A laterally perforated tubular element 34 is formed with flared ends 35 and 36 which are seated respectively against the shoulders 31 and 32. The intermediate portion of the tubular element 34 is formed with lateral perforations 37 which preferably correspond in number and position to the perforations 33. A strainer, which is generally indicated by the numeral 38, is disposed in the space between the tubular element 34 and the working tube 29, between the apertures 33 and 37.

This strainer 38 may be of a construction more clearly illustrated in Figs. 3 and 4, in which 39 indicates a coarse wire screen, 40 indicates a relatively fine wire screen and 41 indicates a piece of fabric between the coarse and fine wire screens. It will be seen, therefore, that when oil is being pumped through the inner tube 21 and tubular element 34, a portion of the oil passes through the perforations 37, and is thereby strained and immediately deposited upon the inner surface of the working barrel 15. A part of this strained and filtered oil enters the joint between the outer tube 20 and the working barrel, a part of it enters the joint between the outer tube 20 and the working tube 29, and a part passes down between the working valve and the inner surface of the working barrel, thereby thoroughly lubricating all the working and removable parts with oil from which the sand and grit has been eliminated.

In order that the strainer and filtering device may have the maximum efficiency, packing rings 42 are provided at each end of the strainer 38.

Although this embodiment of the invention is described very specifically, it is not intended to limit this invention to these exact details of construction and arrangement of parts, but changes may be made within the scope of the inventive idea expressed in the description and claims.

What is claimed as this invention is:—

1. An oil-pump comprising a working barrel, a working valve operable therein, and means to strain oil as it is being pumped and to deposit the strained oil on the surface of said working barrel against which said working valve operates.

2. In an oil-pump, a working valve, a tubular member united with and extending upward from the working valve and having perforations extending laterally therethrough, and a strainer covering the perforations.

3. In an oil-pump, a working valve, a tubular member united with and extending from said working valve and having perforations extending laterally therethrough, a perforated tubular member having flared ends which are fitted against the inner surface of the first said tubular member so that its intermediate portion is laterally opposite to and spaced from the first said perforations, and a strainer fitted in the space between the first and second said tubular members.

4. In an oil-pump, a working barrel, a working valve operable therein, a working tube having perforations extending laterally therethrough and having shoulders above and below said perforations, a tubular element having flared ends and a perforated intermediate portion, said tubular element

having its flared ends fitted respectively against said shoulders, a strainer fitted between the perforations of said working tube and said tubular element and providing spaces outlined by said strainer, working tube and tubular element, and packings fitted respectively in said spaces.

5. In an oil-pump, a working barrel, a working valve operatable therein and comprising a ball-cage, a working tube having its lower end secured to the working valve and surrounding said ball-cage, a duplex tube comprising an inner and an outer tube arranged concentrically and forming an annular space which is closed at its upper end and open at its lower end, said working tube extending into said annular space and having sliding engagement with said duplex tube, and an annular strainer in position to 10 strain oil as it is being pumped and to deposit the strained oil on the sliding surfaces of the working valve and working tube.

6. In a pump comprising a working barrel and the tubing connected thereto, the combination of a duplex tube comprising an inner and an outer tube arranged concentrically and forming an annular space which is closed at its upper end and open at its lower end, said outer tube having the 15 periphery of its lower end reduced, said working barrel having the inner surface of its upper end enlarged and removably fitted around the tapered lower end of said outer tube, the remaining part of the working 20 barrel being of slightly less internal diameter than the external diameter of the remaining part of said outer tube, a working valve slidable in said barrel, and a working tube secured to and extended up from said 25 working valve into said annular space and having perforations extending laterally therethrough.

7. In a pump comprising a working barrel and the tubing connected thereto, the combination of a duplex tube comprising an inner and an outer tube arranged concentrically and forming an annular space which is closed at its upper end and open at its lower end, the greater portion of said duplex tube extending above said working 30

barrel and being formed with a threaded boss on its upper end, a flexible washer surrounding said boss and having its periphery fitted against said tubing, a lock nut on said threaded boss and holding said washer in its effective position to prevent sand from gravitating into the space between said tubing and duplex tube, and a piston operatable in said barrel and duplex tube.

8. In a pump-mechanism, the combination of a working valve, including a ball-cage, a working tube united with and extending up from the working valve, a tubular housing having an opening extending axially therethrough and an annular space separated from and surrounding said opening, a sand-trap movable up and down on said housing, and a valve stem extending through said opening and sand-trap and having a head at its upper end and having its lower end secured to said ball-cage, said working tube having its upper end in the annular space of said housing, the head of said valve stem being spaced above said sand-trap to permit the movement of the latter and to permit the operating movement of the valve stem and its adjuncts relative to said housing, said head being screw threaded for connecting it with an operating rod.

9. In a pump-mechanism, a working valve, a laterally perforated working tube united with and extending up from said working valve, a housing having an annular space into which said working tube extends, 85 said housing having a passage extending therethrough, a valve stem extending through said passage and having its lower end united with said working valve, said valve stem having a head on its upper end, 90 and a cushioning spring supported on said housing in the path of movement of said head, said head being connectible with suitable means for reciprocating it.

In testimony whereof I have hereunto set my hand.

JAMES K. PUTNAM.
